(No Model.)

H. C. BUDDENBERG.
SANITARY CATCH BASIN.

No. 340,694.

Patented Apr. 27, 1886.

UNITED STATES PATENT OFFICE.

HENRY C. BUDDENBERG, OF CINCINNATI, OHIO.

SANITARY CATCH-BASIN.

SPECIFICATION forming part of Letters Patent No. 340,694, dated April 27, 1836.

Application filed November 24, 1885. Serial No. 183,906. (No model.)

To all whom it may concern:

Be it known that I, HENRY C. BUDDENBERG, a citizen of the United States, residing at Cincinnati, Hamilton county, State of Ohio, have invented a new and useful Sanitary Catch-Basin, of which the following is a specification.

My invention relates to improvements in such catch-basins in which accumulate the deposits of several water-closets or seats prior to their running off through a joint outlet to a sewer-trap and branch sewer into the main sewer.

The object of my invention is to provide a catch-basin which meets all sanitary requirements, that is odorless, dilutes the excrements in such a manner as to prevent their accumulation or sticking to the walls and floor of the basin, and insure a quick and complete emptying of it through the outlet to the sewer. I attain these objects by the construction illustrated in the accompanying drawings, in which—

Figure 1 is a longitudinal section of my device at the line 1 1, Fig. 2. Fig. 2 is a horizontal section at the line 2 2 of Fig. 1. Fig. 3 is a central vertical section, and Fig. 4 is a top view, of my grate. Fig. 5 is a longitudinal section of a slightly modified form of my device.

My improved sanitary catch basin (shown in Fig. 1) may serve for two or four seats or water-closets, C C, and consists, next, in the four vertical surrounding walls A A' A'' A''. One of these walls, A', is only partly vertical. The lower portion of it assumes the character of an inclined plane, a, and runs toward the grate B. The other three walls continue vertically down. Two more smaller inclined planes, a' a'', start from the walls A A'', and converge also toward the grate. Thus the three inclined planes a a' a'', in conjunction with wall A'', form a funnel which guides all matter and excrements at once toward the grate, preventing any accumulation elsewhere.

On the outer side of wall A' a smaller basin or reservoir, D, is built, using part of the vertical portion of this wall as an inclosure therefor. Into this basin discharge all waste-water pipes from the house, such as pipes leading from sinks, wash-stands, bath-tubs, &c.; also the rain-water from the gutters. They may enter this basin separately as they come from

the building, as shown at d d, Figs. 1 and 2; or they may join before and enter the basin through one pipe, as at d'. Fig. 5.

In the vertical portion of wall A', near the top of the inclined plane a, and level with the bottom of reservoir D, are several small apertures, c. These apertures are so large and numerous as to suffice to discharge the water about as quick as it enters, to prevent any rising or backing up in case of heavy rain. As they are distributed across the whole width of the basin and wall A', the streams of water issuing therefrom (see arrow, Fig. 1) will reach and flush every part of inclined plane a, on which all of the excrements drop.

My grate B consists of a series of grate-bars, b, which start from a flanged piece, b', and converge upwardly toward a top piece, b''. This top piece has an opening, b'', by which the grate, which sits loosely on the vertical portion of the trap E, may be lifted out for cleaning the latter. I prefer this vertical grate, as it does not clog up as easy as a horizontal one would in case large quantities of offal should be thrown upon it at once. In case the grate should get obstructed once, an overflow, F, which connects with the trap E, prevents the basin from getting filled up.

My form shown in Fig. 5 may be employed when there are more water-closets or seats to be taken in. As shown, it may serve for four or eight seats.

Instead of only one end wall forming an inclined plane, the two end walls, A' and A'', form each one an inclined plane, a and a'', respectively, which converge toward the grate in the center.

I do not confine myself to the material of which the surrounding walls and inclined planes may be constructed. The vertical walls may be brick-work, while the oblique walls and top of reservoir D may be stone flagging. In all cases, however, the basin and auxiliary basin have to be constructed water-tight, which is best done by providing the inside with one or more coats of cement plaster.

A catch-basin constructed as described above is almost odorless, as the constant emptying of waste-water in a house provides a flushing and diluting agent which prevents any accumulation at the bottom or formation of scum at the sides and removes the excrements

to the trap almost as quick as they are deposited.

I claim—

1. In a catch-basin, the combination of a preliminary liquid-waste receiver, D, having discharge-openings *c*, with inclined plane *a*, the former's floor being about level with highest point of the latter.

2. In a catch-basin, the combination of liq-

uid-waste receiver D with inclined plane *a* to and grate B.

In testimony of which invention I hereunto set my hand.

HENRY C. BUDDENBERG.
